UNITED STATES PATENT OFFICE.

BIRNEY W. JACKSON, OF PHILADELPHIA, PENNSYLVANIA, ASSIGNOR TO ALBERT GRIMSHAW, OF PHILADELPHIA, PENNSYLVANIA.

DOUBLE AUTOMATIC DOOR-SPRING AND WEATHER-STRIP.

1,184,243.

Specification of Letters Patent. Patented May 23, 1916.

Application filed August 25, 1914. Serial No. 858,534.

To all whom it may concern:

Be it known that I, BIRNEY W. JACKSON, citizen of the United States, residing at Philadelphia, in the county of Philadelphia and State of Pennsylvania, have invented certain new and useful Improvements in Double Automatic Door-Springs and Weather-Strips, of which the following is a specification.

10 My invention relates to new and useful improvements in weather strips of the type employed in connection with doors particularly.

The principal object of my invention is to 15 provide a weather strip which may be freely connected to an ordinary door and is accompanied by a yieldable means for normally holding it in sealing engagement with the threshold so as to prevent the entrance into 20 the house or room of any dust or other foreign matter.

In connection with the above stated object I aim further to provide for the weather strip a yieldable means which will automatically swing the lower edge of the strip upwardly into spaced relation to the threshold when the door is being opened, thereby guarding against the sticking of the strip on the threshold or floor.

30 A further object is to so attach the yieldable means which controls the lifting of the strip when the door is opened that it (the yieldable means) serves as a means for normally holding the door in closed position.

35 Another object is to construct the weather strip, the means which normally hold it in sealing engagement against the threshold, and the yieldable means which normally holds the door closed and serves to lift the strip when the door is opened, with such regard to proportion, number, and arrangement of parts that the device may be cheaply manufactured, will be durable and efficient in service, and may be readily and easily applied to any door without requiring any alteration in the casing or the door.

The above recited and other incidental objects of a similar nature, which will be hereinafter more specifically treated, are 50 accomplished by such means as are illustrated in the accompanying drawings, described in the following specification, and then more particularly pointed out in the claims, which are appended hereto and form 55 a part of this application.

With reference to the drawings, wherein there has been illustrated the preferred embodiment of this invention as it is reduced to practice, and throughout the several views of which similar reference numerals designate corresponding parts, Figure 1 is a perspective view of a door equipped with my invention, the door being shown in closed position, Fig. 2 is a perspective view showing the door in open position and the weather strip in raised position, and Fig. 3 is a detail perspective view of the leaf spring which normally holds the door closed and the rod which connects the leaf spring to the weather strip.

In the accompanying drawings, I have shown my invention as applied to a door 10 which is of conventional design and is hinged in the usual manner within a door casing 11.

My invention includes as its essential elements, a weather strip 12, a pair of leaf springs 13 and 14 which normally serve to hold the strip in sealing engagement against the threshold of the door casing, a leaf spring 15 which is secured at one terminal to the adjacent walls of the room or building and at its other terminal to the door, and normally serves to maintain the door in closed position, and a lifting rod 16 which is freely connected at its upper terminal to the member 15 and similarly secured at its lower terminal to the weather strip 12.

The weather strip 12 includes a body plate 17 which may be of wood, metal, or composition according to which material may be found most desirable. In a kerf formed in the lower edge of this member 17 there is secured by any suitable fastening devices a sealing strip 18 which may be of fabric, rubber, or any other material which is flexible and will, therefore, form an air-tight joint between the lower edge of the door and the threshold of the door casing.

In securing the weather strip to the lower edge of the door, I employ, as previously stated, a pair of leaf springs or hinge members 13 and 14. The upper terminals of these springs or hinge members are secured to the face of the door by screws or other similar fastening devices while the lower terminals are free with respect to the door and are fixedly secured to the member 17.

The door spring 15 is, as previously stated, formed of leaf steel and is of such

length that its one terminal may be secured to the adjacent wall of the room or building and its other terminal secured to the door. For this purpose, one terminal of the member 15 is longitudinally twisted through an arc of 180° to produce the apertured terminal ear or wing 19 which lies in a plane extending at right angles to the plane of the body of the member 15. Screws or any other suitable fastening means which may be found desirable may be employed in securing this member 19 to the door. The other terminal of the member 15 is apertured to receive the bolt 20 which is freely received in the head 20' of a wood screw bolt A. The member A is, of course, threaded into the door casing as shown in Figs. 1 and 2. It will be observed that the spring may swing about the member A as the central axis when the door is moved from open to closed position, or vice-versa. At the approximate central point of the member 15, there is formed a notch, the terminals 21 of which form shoulders serving to hold an attaching clip 22 against longitudinal movement. This attaching clip 22 is also formed from a strip of sheet metal which is doubled at its central point and is engaged about the member 15. The folded portion of the member 22 is seated within the notch 21 as will be readily observed upon reference to Fig. 3. Rivets or similar fastening devices 23 are passed through the two arms of the member 22 and are positioned immediately adjacent the edge of the member 15. It will thus be seen that the screws 23 in connection with the terminal shoulders produced by the formation of the notch referred to serve to hold the attaching clip against longitudinal movement on the spring 15. The outer terminal of the attaching clip is apertured as indicated at 24 to receive the rounded upper terminal of the rod 16. A pair of nuts 25 are threaded on the terminal of this rod and are engaged against the upper and lower faces of the clip so as to hold the rod against vertical movement thereover. The lower terminal of the rod member 16 is bent to form a hook 26 which is adapted to be removably engaged in an ordinary screw eyelet or similar element 27, carried by the body portion 17 of the weather strip.

The actual construction of the several parts of my invention having been thus disclosed, it now remains to explain briefly the manner in which the various elements operate when the device is in use. In this connection, it will, of course, be apparent that the leaf springs 13 and 14 normally tend to engage flatly against the face of the door in such manner that the flexible sealing strip 18 is engaged with the threshold of the door casing forming an air-tight closure which will prevent the entrance of dust or the like into the room or building. When the door

is opened against the tension of the spring 15, the central portion of this member is bowed upwardly in the manner shown in Fig. 2. This bowing of the spring upon the opening of the door, of course, results in the lifting of the rod 16. As a consequence, the member 17 is pulled upwardly against the tension of the springs 13 and 14 in such manner as to space the flexible sealing strip 18 from the threshold or floor.

From the foregoing description and after a perusal of the accompanying drawings, it will be noted that my invention provides a spring 15 which serves the two-fold function of normally holding the door in closed position and of lifting the weather strip from engagement with the threshold or floor upon the opening of the door.

As shown in the accompanying drawings, it may be advisable to form the lifting rod 16 in two sections which are threaded at their adjacent terminals and are connected by a turn buckle 28. This construction of the lifting rod, of course, enables the user of the device to adapt the rod for use in connection with different doors. If the construction of the door is such as to necessitate the securing of the spring 15 adjacent its lower terminal, the rod 16 can be shortened by means of the turn buckle so as to accommodate it to the position of the spring. If on the other hand, the particular construction of the door makes it necessary to place the spring 15 at a higher point, the rod 16 can be elongated by the turn buckle. On the other hand, if my device is manufactured in large quantities for use in connection with doors which are of similar lines, the rod members 16 can be made as a one-piece device, thus reducing the cost of manufacture.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when required, without sacrificing any of the advantages of this invention, as defined in the appended claims.

Having thus described my invention, what I claim and desire to secure by Letters Patent:—

1. The combination with a door, of a weather strip, resilient means securing the weather strip to the door and normally holding the said strip in engagement with the floor, and a resilient member freely and adjustably connected to the weather strip for lifting the same upon the opening of the door, said resilient member serving also

to normally maintain the door in closed position.

2. The combination with a door, of a weather strip, leaf springs hingedly connecting the weather strip to the door and normally serving to hold the same in engagement with the floor, a leaf spring secured at one terminal to the door and at the other terminal to the door casing and normally holding the door in closed position, and means freely connecting the second mentioned spring and the weather strip whereby the strip is lifted and disengaged from the floor upon the opening of the door.

3. The combination with a door, of a weather strip, leaf springs freely securing the strip to the door and normally serving to hold the strip in engagement with the floor, a leaf spring fixed at one terminal to the door and freely connected at its other terminal to the door casing, and means connecting the second mentioned spring and the weather strip, whereby the strip is automatically lifted into spaced relation to the floor upon the opening of the door.

4. The combination with a door, of a weather strip, and resilient means connected to the strip for automatically lifting the same into spaced relation to the floor upon the opening of the door, said means also serving to normally hold the door in closed position.

5. The combination with a door, of a weather strip, resilient means freely connecting the strip and the door and normally holding the strip in engagement with the floor, resilient means rigidly connected to the door and freely connected to the door casing for normally holding the door in closed position, and a rod member freely connecting said last mentioned resilient

means and the strip, whereby the strip is lifted into spaced relation to the floor upon the opening of the door.

6. The combination with a door, of a weather strip, means resiliently connecting the strip to the door and normally holding the strip in engagement with the floor, a leaf spring connected at one terminal to the door and at the other terminal to the door casing, said spring being disposed to normally maintain the door in closed position, a clip member secured to the spring, and a rod member freely secured at its upper terminal to the clip and at its lower terminal to the strip, whereby the strip is automatically lifted into spaced relation to the floor upon the opening of the door.

7. A device of the character described including a leaf spring adapted to be terminally secured to a door and to a door casing, the said spring being disposed to normally maintain the door in closed position and being provided intermediate its length with a notch, a substantially U-shaped clip member embracing the spring and having its bight portion seated in said notch whereby the clip is held against longitudinal movement upon the spring, a rod member removably secured at its upper terminal to the clip and being adapted to be freely secured at its lower terminal to a weather strip hingedly mounted upon the door whereby the strip is automatically lifted into spaced relation to the floor upon the opening of the door.

In testimony whereof I affix my signature in presence of two witnesses.
